UNITED STATES PATENT OFFICE.

JAMES H. BECK, OF BROOKLYN, NEW YORK, ASSIGNOR TO MERGENTHALER LINOTYPE COMPANY, A CORPORATION OF NEW YORK.

JUSTIFYING SPACER OR SPACE BAND.

1,424,870.

Specification of Letters Patent. Patented Aug. 8, 1922.

Application filed March 28, 1921. Serial No. 456,330.

To all whom it may concern:

Be it known that I, JAMES H. BECK, a citizen of the United States, residing at Brooklyn, in the county of Kings and State of New York, have invented certain new and useful Improvements in Justifying Spacers or Space Bands, of which the following is a specification, reference being had therein to the accompanying drawing.

- 10 This invention relates to justifying spacers or spacebands, such as are use in commercial linotype machines for the justification of composed matrix lines preparatory to the slug casting operation. As heretofore constructed, these spacebands frequently become bent or broken, due to the very rough usage to which they are subjected in practice, and moreover, their manufacture is slow, tedious and expensive.
- 20 The present invention, generally speaking, is directed to an improved form of spaceband which not only possesses greater strength and durability than the old form above referred to, but which in addition can be manufactured with greater ease and facility and at less expense. The manner in which these results are obtained will be best understood from the detailed description to follow.
- 30 Referring to the drawings:

Fig. 1 represents a composed line of matrices in justified condition and ready for casting;

Figs. 2 and 3 are side or face views of the improved spaceband, taken from the left and right, respectively;

Fig. 4 is a side view, taken from the right, of the old form of spaceband;

Figs. 5 and 6 are transverse sections taken 40 on the lines 5-5 and 6-6 respectively of Fig. 3; and

Fig. 7 is a transverse section taken on the line 7-7 of Fig. 4.

As shown in Fig. 1, the improved spaceband comprises two oppositely tapered or wedge-shaped members A and B, whose outer faces are vertical and whose inner engaging faces are inclined at the same angle so that the outer faces will remain parallel at all times. The shorter member A is the stationary part, being provided at its upper end with supporting ears A¹ which hold it against movement during justification, while the longer member B is the movable part, being slidably connected to the member A in

such manner as to be thrust upwardly through the composed line in performing the justifying action.

The foregoing description is equally applicable to the old form of spaceband illus-

trated in Figs. 4 and 7 and comprising the relatively stationary member X formed with the supporting ears X¹, and the movable member Y. In this old form, the sliding connection between the two members is made

up of the longitudinal dovetail slot Y¹ formed in the member Y and the corresponding tongue X² formed on the member X.

Due to the tapered form of the member Y, its marginal bars Y² are quite thin (particular at their upper ends) and hence become bent or broken in use. Moreover, because of buckling or warping or from other causes, these two marginal bars oftentimes

get out of true and interfere with the free sliding movement between the two wedge-shaped members. Other objections and difficulties arise in manufacture: For instance,

in hardening and tempering the member Y, the two marginal bars Y² are drawn out

of parallelism or otherwise distorted, necessitating the shaving-down of their beveled edges to bring them to proper working condition. Such shaving operations, being carried out in the hardened and tempered condition of the metal, are somewhat difficult

and frequently require considerable hand work. Moreover, the nature and extent of these shaving operations necessarily vary on different parts, so that it is seldom that any two come out exactly alike, the dovetail slot

Y¹ being wider on some of the members Y than on others. For this reason, it has been the custom to make the members X with

tongues of slightly different widths so as

thus to compensate for the varying widths of the dovetail slots in the members Y. But even under this practise, there still remains the slow and tiresome task of selecting two members which will properly match; and

furthermore there will be many parts which require additional work before they can be fitted together in a satisfactory manner. A standardized or interchangeable product is

altogether impossible. These and various other objections, both as to manufacture and use, are well known to those skilled in the art and therefore require no further mention.

To obviate the foregoing objections and

to attain the objects before stated, the improved spaceband is constructed as follows: The movable member B is formed with two longitudinal slots B¹ and presents two marginal bars B² (like the corresponding bars Y² of the old spaceband) and an intermediate centrally located bar B³, the latter being considerably wider than the other two and beveled on its opposite edges throughout its length or at any rate for a distance equal to the extent of movement of the member B. The relatively stationary member A is formed on its inner or inclined face with a pair of guides A² arranged in the longitudinal slots B¹ and undercut or dovetailed on their inner edges to receive the bevelled edges of the bar B³. The sliding joint or connection thus formed serves to hold the two wedge-shaped members in proper contacting relation, while permitting the member B to be moved relatively to the stationary member A in expanding and contracting the spaceband as a whole. Thus in Fig. 1, the spacebands are shown in an expanded condition, the movable members B having been pushed upwardly through the composed line of matrices Z to spread out the line to its proper lock-up length. It will be noted (Figs. 3 and 5) that the guides A² do not touch the marginal bars B² but are slidably connected solely with the central bar B³. In this connection, it is also pointed out that the length of the guides A², although the same as that of the tongue X² of the old spaceband, is much greater than the width of the bar B³ (the ratio being more than two to one), thus providing a smooth and easy running engagement between the parts. At their upper ends, the bars B² and B³ merge into a thin connecting web B⁴, the slots B¹ being stopped short of the end of the member B for that purpose; and at their lower ends, the bars are connected together by a longer and much thicker web B⁵ which is left at that end of the member B. Between the two webs, the slots B¹ extend clear through the member B so as to allow the latter to be tapered down to the extent indicated and at the same time permit the guides A² to enter the slots in making sliding connection with the bar B³ without projecting beyond the outer or vertical face of the member B. In assembling the two members A and B, the guides A² are slipped over the lower end of the bar B³ (which, it will be remembered, is bevelled throughout its length), and a headed pin B⁶ is then secured to the web B⁵ at the extreme lower end of one of the slots B¹ in position to engage the lower end of the member A and limit the upward movement of the member B. The downward movement of the member B is limited by the direct engagement of the web B⁴ with the upper ends of guides A², such being the

position of the parts during the circulation of the spaceband through the machine and before justification. In this way, also, the two members of the spaceband are permanently locked together.

The advantages of the improved spaceband will now be clear: Due to the presence of the additional intermediate bar B³, the movable slotted member B is much stronger and far more rigid than the corresponding member Y of the old spaceband, and hence its liability to bending or breakage in use is correspondingly reduced. Moreover, by connecting the guides A² solely with the intermediate bar B³, a very effective sliding connection between the wedge-shaped members A and B is produced. Thus, as the length of the guides A² is much greater than the width of the bar B³, a relatively long and narrow bearing is provided between the parts which renders their running engagement extremely smooth and easy and free from binding. Furthermore, being formed wholly on the integral bar B³, the two bevelled surfaces preserve their true shape and parallelism at all times, as the bar will seldom if ever become distorted under normal conditions. In this connection, it will be remembered that the guides A² are arranged out of contact with the two marginal bars B², so that any distortion or lack of parallelism of the latter cannot affect the sliding connection. In actual practise, the improved spaceband has been found to possess remarkable strength and durability and to be exceptionally efficient in operation.

Other important advantages arise in manufacture: Inasmuch as the beveled surfaces are confined wholly to the intermediate bar B³, the member B may be hardened and tempered without requiring any subsequent shaving or planing of the beveled surfaces. That is to say, these beveled surfaces, being present on a single integral part, may be formed thereon when the metal is in a soft condition and still maintain their true shape and parallelism during the hardening and tempering operations, thereby obviating one of the chief difficulties encountered in the manufacture of the old spaceband. As a result also, the beveled edge bars B² may all be of uniform width to cooperate with guides A² of one uniform width. In this way, the two wedge-shaped members A and B may be made in strictly standardized and interchangeable form and such that any two can be fitted directly together, thus saving an enormous amount of time and labor heretofore required in assembling the parts. In addition, many operations, previously necessary in the case of the old spaceband, are entirely eliminated in the manufacture of the improved spaceband, thereby reducing the cost of manufacture to a minimum.

In the accompanying drawing, the inven-

tion has been shown merely in preferred form and by way of example, and many changes and variations may be made therein and in its mode of application which will 5 still be comprised within its spirit. For example, while the member B as herein illustrated presents but three longitudinal bars, it is apparent that it may be composed of a greater number of desired. In this connection, however, it is pointed out that it is desirable in any case to retain the two marginal bars so as to insure the proper engagement of the spaceband with the mold during casting. Again, in the present embodiment, the central bar B³ is much wider than the marginal bars B², but it is obvious that it could be made narrower or even wider if preferred. It is also pointed out that, in its broader aspects, the invention 10 does not require that the two beveled surfaces be located wholly on the intermediate bar, although such arrangement is more advantageous for the reasons previously noted. It should be understood therefore that the invention is not limited to any specific form 15 or embodiment except in so far as such limitations are specified in the claims.

Having thus described my invention, its construction and mode of operation, what I 20 claim is as follows:

1. A justifying spaceband comprising a relatively stationary wedge-shaped member, and a movable cooperating wedge-shaped member slidably connected thereto, said 25 movable member being slotted and presenting two marginal bars extending in the direction of its movement and an intermediate bar extending in the same direction and serving to add strength and rigidity to the 30 movable slotted member during the justifying action.

2. A justifying spaceband comprising a relatively stationary wedge-shaped member, and a movable cooperating wedge-shaped member slidably connected thereto, said 35 movable member being slotted and presenting two marginal bars extending in the direction of its movement and a wider intermediate bar extending in the same direction and serving to add strength and rigidity to the 40 movable slotted member during the justifying action.

3. A justifying spaceband comprising a relatively stationary wedge-shaped member, and a movable cooperating wedge-shaped member slidably connected thereto, said 45 movable member being slotted and presenting two marginal bars extending in the direction of its movement and an intermediate 50 centrally located bar extending in the same direction.

4. A justifying spaceband comprising a 55 movable slotted wedge-shaped member presenting two marginal bars extending in the 60 direction of its movement and an interme-

diate bar extending in the same direction, and a relatively stationary cooperating wedge-shaped member having guides arranged in the slots of said movable member out of contact with its marginal bars and 70 slidably connected solely with its intermediate bar.

5. A justifying spaceband comprising a movable slotted wedge-shaped member presenting two marginal bars extending in the 75 direction of its movement and an intermediate bar extending in the same direction and beveled on its opposite edges, and a relatively stationary cooperating wedge-shaped member having guides arranged in the slots 80 of said movable member out of contact with its marginal bars and undercut or dovetailed on their inner edges to make sliding connection solely with its intermediate bar.

6. A justifying spaceband comprising a 85 movable slotted wedge-shaped member presenting two marginal bars extending in the direction of its movement and an intermediate centrally located bar extending in the same direction, and a relatively stationary 90 cooperating wedge-shaped member having guides arranged in the slots of said movable member out of contact with its marginal bar and slidably connected solely with its intermediate centrally located bar. 95

7. A justifying spaceband comprising a movable slotted wedge-shaped member presenting a plurality of bars extending in the direction of its movement, and a relatively 100 stationary cooperating wedge-shaped member formed with guides slidably connected to a single one of the longitudinal bars of said movable member.

8. A justifying spaceband comprising a movable slotted wedge-shaped member presenting a plurality of bars extending in the direction of its movement, one of said bars being beveled on its opposite edges, and a relatively 105 stationary cooperating wedge-shaped member having guides undercut or dovetailed on their inner edges to make sliding connection with the beveled-edge bar of said movable member.

9. A justifying spaceband comprising a movable slotted wedge-shaped member presenting two marginal bars extending in the direction of its movement and an intermediate centrally located bar extending in the same direction, and a relatively stationary 115 cooperating wedge-shaped member having guides arranged in the slots of said movable member and slidably connected solely with its intermediate centrally located bar, the length of said guides being considerably greater than the width of the connected bar 120 so as to provide a relatively long and narrow bearing between said parts.

10. A justifying spaceband comprising a 125 movable slotted wedge-shaped member presenting a plurality of bars extending in the 130

direction of its movement, and a relatively stationary cooperating wedge-shaped member formed with guides slidably connected to a single one of the longitudinal bars of said movable member, the length of said guides being considerably greater than the width of the connected bar so as to provide a relatively long and narrow bearing between said parts.

11. An integral movable wedge-shaped ¹⁰ justifying member having a plurality of longitudinal slots cut therethrough and presenting three or more bars extending in the direction of its movement, in the manner and for the purpose described. ¹⁵

In testimony whereof, I have affixed my signature hereto.
